Lawrence Holmes

United States Patent Office.

LAWRENCE HOLMS, OF PATERSON, NEW JERSEY.

Letters Patent No. 96,433, dated November 2, 1869.

IMPROVED WOODEN PAVEMENT.

The Schedule referred to in these Letters Patent and making part of the same.

To all whom it may concern:

Be it known that I, LAWRENCE HOLMS, of Paterson, in the county of Passaic, in the State of New Jersey, have invented certain new and useful Improvements in Wooden Pavements; and I hereby declare that the following is a full and exact description thereof, reference being had to the annexed drawings, making part of this specification, and to the letters and figures of reference marked thereon, in which—

Figure I is an end view of a longitudinal section of the paving-blocks.

Figure II, a side view of a transverse section.

Figure III, a perspective view.

My invention consists, first, in constructing the superstructure of a pavement of wooden blocks, having overlapping portions at their ends and sides, and so cut and adapted to each other as to form longitudinal or transverse channels, or both, to be filled with concrete or cement, said grooves serving to give a foot-hold to animals travelling on the pavement.

It also consists in the construction of a wooden pavement of blocks, having overlapping portions at the ends and sides, with channels, either longitudinal or transverse, or both, between them, which are filled with concrete or cement, said blocks resting on a layer of semi-elastic cement, laid over a concrete substratum, or foundation, as hereinafter specified.

The wooden blocks, seen in the several figures, are cut from planks of proper thickness, and the grain of the wood set in a position perpendicular to the pressure to be sustained.

A, in the several figures, represents the end of the wooden paving-blocks; *a*, the lap, and *b*, the shoulder upon which the lap rests, and which also sustains the concrete filling C of the grooves or channels.

A', Figs. I and III, shows a block, in cross-section, with the lap *a* and shoulder *b* plainly seen.

B, Figs. II and III, shows the side of the blocks,

with the laps *a*, shoulders *b*, and channels *c*, the object of the channels *c* being to prevent the lateral slip of the feet of horses, or other animals, travelling upon the pavement.

C indicates a concrete substratum, or foundation, composed of broken stone or gravel, with hydraulic or other suitable cement.

D, an asphaltic or bituminous lining, interposed between the concrete foundation and the wooden paving-blocks, and upon which the blocks rest and are secured, in the manner heretofore described.

I do not limit myself to the combination of the before-described wooden blocks, for paving-purposes, with a grouted or concrete foundation, with or without an asphaltic or bituminous covering, as my block may be used with other foundations, such as wooden plank, or, in certain favorable localities, without other substratum than the natural bed.

I do not claim, broadly, a wooden pavement, between the blocks of which are channels or grooves, filled with concrete or cement, for such has been used before.

What I claim, in blocks for wooden pavements, is—

1. Wooden paving-blocks, formed with overlapping portions *a* *a'*, and shoulders *b* *b'*, when so cut and adapted to each other as to form either longitudinal or transverse channels *c* *c'*, or both, to be filled with concrete or cement, substantially as herein described.

2. A pavement constructed of wooden blocks, having overlapping portions at the ends and sides, with channels, either longitudinal or transverse, or both, between them, which are filled with cement, said blocks resting on a layer of semi-elastic cement, laid over a concrete substratum or foundation, substantially as herein described.

LAWRENCE HOLMS.
